UNITED STATES PATENT OFFICE.

SEELY MCCORD TERWILLIGER AND WILLIAM TELL SEVENER, OF LOS ANGELES,
CALIFORNIA.

DIRECTION SIGNAL.

Application filed November 9, 1926. Serial No. 147,329.

This invention relates to direction signals of the manually operated type and is particularly directed to a signal device which is especially adaptable for association with road vehicles and more particularly with standard types of motor vehicles.

Traffic laws of many States and common practice have resulted in a certain accepted method of manually indicating contemplated right or left turns or stops, this method requiring the driver to extend his arm and hand outwardly from the vehicle, in a horizontal direction to indicate a contemplated left turn, more or less upwardly to indicate a contemplated right turn, and more or less downwardly to indicate a contemplated stop. It is for this reason desirable that a direction signal mechanism include a semaphore indicating member formed in simulation of a hand. Signal devices having this general character of indicating arm have heretofore been made, but even though painted a light color are distinctly visible and attract attention only when viewed from a relatively short distance in the daytime, and are practically invisible at night unless provided with some means of illumination. It is now generally recognized that a signal which is illuminated will be more visible in the daytime as well as at night and it is a general practice to illuminate the indicating means of such devices by means of a lamp enclosed therein and projecting its rays directly through a colored glass or lens, but in every instance of this kind, in order that such lamp and its filament be not objectionably visible, it is necessary that the glass or lens be of relatively dark color or not fully transparent.

By experiments, we have found that a very superior degree of visibility may be had by means of indirect illumination, with the mechanism arranged to produce an illuminated outline of the indicating element, that by reason of such indirect illumination we may fully utilize a pure white light and at the same time entirely eliminate glare and all possibility of viewing the source of said illumination, and that we can dispense with the glass or lens usually employed.

Therefore, it is an object of the present invention to provide a signal device having a signal element illuminated in outline by indirect illumination.

A further object is to provide a signal device having a semaphore signal member in simulation of a human arm and hand with the hand portion thereof illuminated in outline by indirect illumination.

60

Another object is to provide an illuminated signal member having the source of illumination hid from view by an opaque member of a shape corresponding to that of the desired signal and providing reflecting surfaces adjacent the marginal edges of said opaque member.

65

Another object is to provide a counterbalanced signal arm.

Various other objects and advantages will be more fully apparent from the following description of the accompanying drawing which forms a part of this disclosure, and which illustrates a preferred form of embodiment of the invention.

75

Of the drawings:

Fig. 1 is a plan section through a portion of the windshield and instrument-board of a motor vehicle, showing the signal device of the present invention associated therewith, a portion of the signal arm being shown in the section.

80

Fig. 2 is a front elevation showing the signal arm in upright position, certain portions of the device being shown in section.

85

Fig. 3 is an edge elevation, partly in section, as indicated by line 3—3 of Fig. 2.

Fig. 4 is an enlarged detail section taken on line 4—4 of Fig. 2.

The signal device illustrated in the drawing, includes a signal arm A which is rotatably journaled on the outer end of a supporting bracket preferably secured to the windshield frame 2 of a motor vehicle, and a suitable operating device B preferably secured to the instrument-board in a location convenient for operation by the driver.

90

The signal arm A is adapted to be rotated from a normal non-signaling position, as shown in Fig. 1, to various signaling positions and when in normal position the signaling portion of the arm A is screened from view within a U-shaped shield C which is open at its sides and top to permit the signal arm to swing freely upwards and outwards.

100

The bracket 1 engages the rear wall 3 of the shield C and both are secured to the frame 2 by screws or bolts 4, the front wall 5 of the shield having suitable apertures 6.

110

formed therein in alignment with said screws to permit of the insertion of a screwdriver to engage the screws during installation of the device.

5 Extending laterally from the inner portion of the bracket 1 is a tubular arm 7 in which is slidably guided a toothed rack 8 arranged to engage a pinion 9 secured to the signal arm A and enclosed within a hollow 10 boss 10 formed on the outer end of the bracket arm 7.

While it is realized that the signal arm A may be made of any suitable material and in various manners, the preferred construction herein illustrated consists of two sheet metal members 11-11^a forming opposite sides of the arm, said members being joined together at their peripheral meeting edges by welding or by other suitable means. The 20 pinion 9, previously referred to, is formed on a tubular hub 12 secured in the signal arm A (see Fig. 3) and the signal arm A is rotatably secured to the bracket arm by a hollow pivot bolt 13 which passes through 25 said hub 12 and is secured to said bracket arm by a nut 14.

The means for reciprocating the rack 8 to operate the signal arm, comprises a rod 15 secured in the inner end of said rack, with 30 its opposite end connected to a flexible wire or cable 16 enclosed in a conduit guide 17 leading to the operating device B.

As shown in Fig. 1, the signal arm A is in a non-signaling position within the 35 shield C, when not in use, this normal position of the signal arm being also indicated in Fig. 2 by the dotted outline 33.

By a suitable operation of the device B the wire 16 will be pushed into the conduit 40 17 and will propel the rack 8 outwardly and this outward travel of said rack will by reason of its toothed engagement with the pinion 9 cause the signal arm A to be swung upwardly to the position shown in full lines 45 in Fig. 2, to signal a contemplated right turn. In a similar manner the signal arm A may be swung approximately one-half of a revolution to a horizontal position, as indicated in Fig. 2 by the dotted outline 34, 50 to signal a contemplated left turn, or rotated approximately three-quarters of a revolution to a downward position as indicated in Fig. 2 by the dotted outline 35, to signal a contemplated stop.

55 For the purpose of providing illumination for the signal arm, there is provided an electric lamp bulb 36 mounted within the hand portion thereof, as will be hereinafter explained, one terminal of said lamp being 60 grounded, as indicated at 37 in Fig. 1, and the other terminal thereof being connected to a circuit wire 38. Said circuit wire 38 extends through an opening in the front wall of the signal arm and leads to the axis there- 65 of where it passes rearwardly through the

tubular pivot bolt 13 for connection in series with the operating device B and the battery 43 of the vehicle, said battery being grounded as indicated at 44.

As previously mentioned, the signal element is contoured to represent an open hand and is preferably formed of two sheet metal members 11-11^a. Closely adjacent the outer margin of this hand-shaped signal element the members 11-11^a are each bent inwardly at an angle of approximately 45 degrees to provide opposite reflecting surfaces 45-45^a, the reflecting surface 45 facing forwardly and the reflecting surface 45^a facing rearwardly so that the signal will be equally 70 visible from both the front and rear of the vehicle. 75

The palm portion of the members 11-11^a are cut away to provide a hollow interior defined in extent by the inner edges 46 of said members. Extending forwardly at spaced intervals from the inner edge 46 of the member 11 is a series of ears 47 having their outer ends bent parallel to the plane of the hand, and extending rearwardly from the inner edge of the member 11^a is a similar series of companion ears 48. These respective series of ears support front and rear cover plates 49-50, the front plate 49 being preferably secured to the ears 47 by spot welding and the plate 50 being secured to the ears 48 by screws 51 so as to be conveniently removed for access to the interior of the signal element. Each of the cover plates is contoured similar to the exterior 90 shape of the hand portions of the members 11-11^a but are of a reduced size so as to leave an open space between their peripheral edges and the respective reflecting surfaces 45-45^a, as shown in Figs. 2 and 4. 95

The arm member 11 also has a relatively narrow bridge 52 which supports the lamp 36, said bridge having a half round central portion forming one-half of a lamp socket, the other half thereof being formed of a 100 strap member 53. One end of the member 53 has a tang 54 engaging in an aperture 55 in the bridge 52 while its opposite end is secured to said bridge 52 by a screw 56, this arrangement providing a clamp socket in 105 which the lamp 36 is rigidly held in place and eliminates the difficult operation of screwing the lamp into a screw threaded socket in the usual manner. 110

In practice it is preferable to finish the exterior surfaces of the arm and hand portions of the signal arm A and the outer surfaces of the cover plates 49 and 50, in a dark color (preferably black), and to finish the angled reflecting surfaces 45 and 45^a 115 and the interior surfaces of the hand, in a light color (preferably white) so as to be highly reflective, thus to take full advantage of the maximum illumination afforded by the lamp. 120 125 130

The light rays emanating from the lamp will be projected onto the angled reflecting surfaces and thence outwardly in opposite directions, as indicated in Fig. 4 of the drawing, through the open space between said reflecting surfaces and the marginal edges of the cover plates 49—50, to thus produce a signal element illuminated in outline by indirect illumination, with said outline contoured in simulation of a human hand. In a signal element of this character the lamp is hid from view by the opaque cover plates and the available value of the light rays are not diminished by having to pass through colored glass or lenses.

It is further to be noted that the end of the arm A extends beyond its point of pivotal securance to the bracket, in a direction opposite that of the hand portion, and that this extended portion is weighted by suitable material 57 so as to counterbalance the signal arm A and render it easy to be operated by the flexible wire or cable 16.

While the specific embodiment herein illustrated and described is fully capable of fulfilling all of the objects primarily stated, it is to be understood that we do not wish to limit the invention in this regard, for it is susceptible of embodiment in various other forms, all coming within the scope of the claims, which follow.

We claim as our invention:

1. In a signal element provided with indirect illumination, the combination of: a hollow body having a peripheral reflecting surface angled inwardly and contoured to define the shape of the desired signal symbol; a source of illumination within said hollow body; and a cover plate obscuring said source from view, said plate being contoured to correspond to the shape of the desired signal symbol and of slightly smaller size than the outer periphery of said reflecting surface and spaced therefrom to provide a light passage outlining the symbol.

2. In a signal element provided with indirect illumination, the combination of: a hollow body having front and rear peripheral reflecting surfaces angled inwardly and contoured to define the shape of the desired

signal symbol; a source of illumination within said hollow body; and front and rear cover plates obscuring said source from view, each plate being contoured to correspond to the shape of the desired signal symbol and of slightly smaller size than the outer periphery of the adjacent reflecting surface and spaced therefrom to provide a light passage outlining the symbol.

3. In a signal element provided with indirect illumination, the combination of: a hollow body having a peripheral light passage contoured to define the shape of the desired signal symbol; an angled reflecting surface adjacent said passage and coincidentally contoured; and a source of illumination within said body, the walls of the body being opaque so as to hide said source from view.

4. In a signal element provided with indirect illumination, the combination of: a hollow body having a peripheral reflecting surface angled inwardly and contoured in simulation of a human hand; a source of illumination within said hollow body; and a cover plate obscuring said source from view, said plate being contoured in simulation of a human hand and of slightly smaller size than the outer periphery of said reflecting surface and spaced therefrom to provide a light passage outlining the hand-shaped signal.

5. In a signal element provided with indirect illumination, the combination of: a hollow body having front and rear peripheral reflecting surfaces, each angled inwardly and contoured in simulation of a human hand; a source of illumination within said hollow body; and front and rear cover plates obscuring said source from view, each cover plate being contoured in simulation of a human hand and of slightly smaller size than the outer periphery of the adjacent reflecting surface and spaced therefrom to provide a light passage outlining the hand-shaped signal.

In testimony whereof, we have hereunto set our hands at Glendale, California, this 3rd day of November, 1926.

SEELY McCORD TERWILLIGER.
WILLIAM TELL SEVENER.
